UNITED STATES PATENT OFFICE.

EDWARD L. MILLER, OF CHICAGO, ILLINOIS.

AUTOMATIC RECORDING INSTRUMENT.

SPECIFICATION forming part of Letters Patent No. 568,784, dated October 6, 1896.

Application filed January 10, 1893. Serial No. 457,900. (No model.)

To all whom it may concern:

Be it known that I, EDWARD L. MILLER, a citizen of the United States, residing at Chicago, in the county of Cook and State of Illinois, have invented certain new and useful Improvements in an Automatic Recording Instrument, of which the following is a full, clear, and exact description, that will enable others to make and use the same, reference being had to the accompanying drawings, forming a part of this specification.

This invention relates to that class of devices that are adapted to be attached to the various types of steam, air, gas, and liquid pressure gages for the purpose of automatically and accurately recording the working thereof and making permanent record, whether the action is of a regular or irregular character.

The device is adapted for general purposes and may be used in connection with many kinds of different mechanical appliances, whether under pressure or not.

In the drawings, Figure 1 is a front elevation of a device embodying my improved features; Fig. 2, a vertical section of the same, on line 2, Fig. 1, looking in the direction indicated by the arrow; Fig. 3, a horizontal section on line 3, Fig. 1; Fig. 4, a broken-away sectional detail on line 4, Fig. 1; Fig. 5, a similar view on line 5, Fig. 1; Fig. 6, a horizontal section on line 6, Fig. 5. Figs. 7 and 8 are face views of a disk-wheel; Fig. 9, a section of the same on line 9, Fig. 10; Fig. 10, a transverse section on line 10, Fig. 7; and Fig. 11, a horizontal section on line 11, Fig. 2, the inclosing case being omitted.

The device is shown in connection with an ordinary pressure-gage for the purpose of illustrating a practical working application of the invention, motion being, in this instance, transmitted to the recording attachment from the gage-spindle on which the indicating-hand is mounted.

A is a steam-pressure gage of the ordinary type; A', the flattened circular spring-tube, connecting at one end with a lever operating a segment-gear, (not shown,) which engages with a pinion A², mounted on the rotatable gage-spindle A³, carrying the indicating-hand A⁴.

A pinion B is rigidly mounted on the outer end of spindle A³ and engages with the adja-

cent toothed edge a of the lower part of a rack-bar B', having an endwise movement across the face of the gage. A friction-roller 55 a' prevents a lateral movement of the rack-bar and holds the same into engagement with the pinion B. The rack-bar extends up through a guide a², Figs. 3 and 11, into a case or box receptacle C, mounted on top of the 60 gage and inclosing the recording mechanism. The upper part of the rack-bar, moving in the inclosing casing, is provided on the inner side with a series of teeth a³, Fig. 2, engaging with a pinion a⁴, rigidly mounted on a 65 hub extension a⁵, Fig. 11, of a disk wheel C', which is in turn loosely mounted on a worm-shaft C², the respective ends of which are journaled in companion standards a⁶, secured to the inside bottom of the inclosing case. 70

A ratchet-pinion C³, Figs. 1, 3, 4, and 11, is rigidly mounted on the worm-shaft adjacent to the disk wheel C'. This disk wheel is provided with a recess a⁷, Fig. 8, in which is mounted an angular dog C⁴, Figs. 7, 10, and 75 11, the outer end a⁸ of which extends over into engagement with the pinion C³ in one-way operation. A spring b is seated in a chamber b' in the disk wheel and bears on the turned-in end b², Fig. 10, of the dog C⁴ and 80 serves to retain the opposite end thereof in engagement with the pinion C³. A spring-pressed pawl b³, Fig. 4, is also held in engagement with pinion C³ and locks the same against a back movement with the disk wheel. 85

When the rack-bar B' moves upwardly, the pinion a⁴, disk wheel C', worm-shaft C², and ratchet-pinion C³ all rotate together in one direction. On the down movement of rack-bar the pinion a⁴ and the disk wheel C' are 90 rotated in the opposite direction, the ratchet-pinion and worm-shaft remaining stationary.

A hollow shaft or sleeve b⁴ loosely incloses the lower part of a stationary spindle D, having its lower end, Fig. 5, fixed in the bottom 95 part of case C. A worm gear-wheel b⁵ is rigidly mounted on the hollow shaft and engages with the worm end b⁶ of shaft C². The hollow shaft is provided on the upper end with a flange b⁷, Figs. 1 and 5, corresponding to the 100 flanged end b⁸ of a spool D', loosely mounted on spindle D and resting on flange b⁷. These contacting flanges are perforated, as at d, for the insertion of a locking-pin d', which se-

cures the spool and sleeve together and imparts the required rotary movement to the spool from the worm-shaft.

By the arrangement described an intermittent rotary movement is transmitted to the spool D' in one direction only, and that from the up movement of the rack-bar.

A spool D² carries a roll of paper or other material d², on which the required record is to be noted. The paper ribbon, as it is unwound from spool D², passes on its way to the driven spool between a guide-plate d³ and a bracket d⁴. The paper rests upon the bracket d⁴ to receive the impression of a pencil or recording-point g, Fig. 2, inserted in the rack-bar and projecting through a slot g' in the guide-plate d³, Fig. 1.

In operation an endwise movement is transmitted to the rack-bar by the oscillatory action of the gage-spindle and the vibratory movement of the gage-hand accurately transcribed in vertical and diagonal lines on the paper ribbon, as shown at h, Fig. 1.

A pointer h' is mounted on the upper end of rack-bar B' and traverses the graduated-scale surface h².

Having thus described my invention, what I claim as new, and desire to secure by Letters Patent, is—

1. In a recording instrument, the combination with a pressure-gage, of a rack-bar, adapted to receive an endwise reciprocating movement therefrom, a pinion, engaging the upper end of said rack-bar, a disk wheel, having an elongated hub on which said pinion is

rigidly mounted, a worm-shaft, on which said disk wheel is loosely mounted, a ratchet-pinion, rigidly mounted on the worm-shaft, a spring-pressed dog, mounted in said ratchet-wheel and engaging said ratchet-pinion, a spring-pressed pawl, locking the ratchet-pinion against a back movement, a spool, on which the record-ribbon is wound, and means for connecting said shaft and spool, whereby an intermittent rotary motion is transmitted to the spool coincident with the movement of the rack-bar, substantially as described.

2. In a recording instrument, the combination with a pressure-gage, of a rack-bar, receiving a reciprocating endwise movement from the spindle of said gage, a disk wheel, having an elongated hub, a pinion, rigidly mounted on said hub and with which said rack-bar engages, a worm-shaft, on which said disk wheel is loosely mounted, a ratchet-wheel, rigidly mounted on the worm-shaft, a spring-pressed dog, mounted in the disk wheel and engaging the ratchet-wheel, a spring-pressed pawl, engaging with and locking said ratchet-wheel against a back movement, a hollow shaft, provided with a flange, a pinion, mounted thereon and engaging with the worm-shaft, a receiving-spool, and means for connecting said hollow shaft and spool in a rotary movement, substantially as set forth.

EDWARD L. MILLER.
